By Charles N. Woodward ATTORNEY.

UNITED STATES PATENT OFFICE.

JOHN WALTER STEVENS, OF ST. PAUL, MINNESOTA.

SEAL FOR SEAL-LOCKS.

SPECIFICATION forming part of Letters Patent No. 695,418, dated March 11, 1902.

Application filed May 22, 1900. Serial No. 17,615. (No model.)

To all whom it may concern:

Be it known that I, JOHN WALTER STEVENS, a citizen of the United States, residing at St. Paul, in the county of Ramsey and State of Minnesota, have invented certain new and useful Improvements in Breakable Seal-Plates for Seal-Locks, of which the following is a specification.

This invention relates to seal-locks; and it consists in the construction of a breakable seal-plate to be used in connection with seal-locks, as hereinafter shown and described, and specifically pointed out in the claims.

In the drawings illustrating the invention, Figure 1 is a perspective view of one of the breakable seal-plates from the "faceside," and Fig. 2 is a similar view from the reverse side. Figs. 3 and 4 are views similar to Fig. 2, illustrating modifications in the structure. Figs. 5 and 6 are perspective views of the seal-plate, illustrating the manner of actuating it.

Prior to the designing of the present seal but limited success only was attained in the use of articles of this sort for the purpose for which they are designed—namely, the sealing of car-locks in such way that the seal is broken upon the occurrence of any tampering with the lock to such extent as to enable the door to be opened. As is well known, the freight-cars of the railway systems of the United States are constantly being transferred from one system to another under the rules permitting such cars not only to be thus transferred, but to be used for return loading by the system upon whose tracks it was last previously unloaded. Again, it is well known that the different railway systems vary with respect to the relative arrangement of the doors, locks, and doorways, in some cases the doors being arranged to move to the right in opening and in others to the left, this requiring that the locks shall be correspondingly variously placed. In consequence of this most seals of the present class have not been very successful, because of the fact that they were applicable for use only with locks of one or the other of the two sorts referred to.

One of the principal purposes of the present invention is to provide a seal which can be interchangeably used with freight-car locks of any of the ordinary makes and ar-

ranged either on the right or the left of the door.

Another important object is to form the seal in such way that it shall be uniformly thick throughout from face to face.

Heretofore the proposal has been to employ face projections as the means for engaging with the seal-retainer. On the contrary, in the present case, the seal being formed as a flat plate, the retaining element consists of a series of indentations in the side edges extending entirely through the seal from one broad face to the other, thus forming the equivalent of a series of two or more teeth. As these recesses are similar, there is assurance provided by having such series that in case of breakage or marring of either of the teeth the seal will nevertheless engage properly with the retaining device.

In the drawings the seal-plate is indicated as a whole by A, it being formed, as usual, of some fragile material, as clay, glass, or other similar substances. The front broad face is indicated by a and the rear face by a', these being parallel to each other throughout, the seal being, as aforesaid, uniformly thick from edge to edge. In each of two of its opposite edges, as at a² a³, it is formed with a series of recesses b, providing a corresponding series of teeth b'. The two series of recesses and teeth are in the same relative positions on the longitudinal lines of the seal, and consequently it can engage with a retaining-wheel B, such as shown in Fig. 5, on the right-hand side or with a similar retaining-wheel on the left-hand side, as shown in Fig. 6.

It is unnecessary herein to illustrate or describe in detail all of the parts of the lock with which the seal is used, they being now well-known and one lock being the counterpart of another, except, as aforesaid, that there is an inversion in the relative positions of the retaining-wheel and other parts to correspond to the different positions in which the locks are placed in relation to the car-door. Figs. 5 and 6 illustrate sufficiently the means of retaining the seal in place.

The seal-plate will preferably be provided with weakening channels or cavities d, as shown, to provide means for insuring the fracture of the plate when a sufficient pres-

sure is brought to bear against it. This channel or recess may be in any required form or at any required point in the plate, but will preferably be in the rear face of the plate, as shown. These channels or recesses may be in any required shape, either in the form of a straight channel open at the ends, as in Figs. 1 and 2, a straight channel closed at the ends, as in Fig. 3, or in the form of a series of holes or cavities, as in Fig. 4, or in any other desired shape which will "weaken" the plate to render its fracture more certain. By reason of the presence of the weakening channels or recesses the plate will yield and break under a much less pressure than the plate without the weakening channels.

Having thus described my invention, what I claim as new, and desire to secure by Letters Patent, is—

1. As a new article of manufacture, a seal-plate consisting of a plate of fragile material having on each of two opposite edges a series of alternating indentations and teeth having reversely angular sides, and adapted to en-

gage with a movable retaining device having correspondingly alternately disposed angular teeth and indentations, whereby it is adapted to engage with a retaining device at either edge, substantially as set forth.

2. As a new article of manufacture a seal-plate consisting of a flat plate of uniform thickness throughout and having a series of alternating indentations and teeth having reversely angular sides at its edge, each extending entirely through from the front to the back face, and each indentation of the series being a counterpart of the other whereby the engagement of the seal with the retaining device by one or another of the said serrations or teeth is insured, substantially as set forth.

In testimony whereof I have hereunto set my hand in the presence of two subscribing witnesses.

JOHN WALTER STEVENS.

In presence of—

HELEN G. COTTON,
C. N. WOODWARD.
